FLUID IRRADIATOR

Merrill J. Dorcas, Berea, Ohio, George C. Supplee, Bainbridge, N. Y., and Frank Remesch, Jr., Parma, Ohio, assignors of one-half to The Borden Company, a corporation of New Jersey, and one-half to National Carbon Company, Inc., a corporation of New York

Application April 2, 1935, Serial No. 14,206

15 Claims. (Cl. 250--49)

This invention relates to apparatus for the irradiation of liquids with radiant energy and more especially to the radiation of liquid food stuffs, such for example as milk, with ultra-violet energy whereby an increase in vitamin content is secured. The radiation of such substances as milk with ultra-violet energy produces what is known as anti-rachitic activation and this activation is generally attributed to an increase in the vitamin content. However, the particular wave length of energy employed and the particular type of activation secured forms no part of the present invention since the apparatus may be employed with liquids of any type and with energy from any source.

An object of our invention is to devise an improved apparatus for the irradiation of liquids. Another object of our invention is to secure an even distribution of the film of liquid over the supporting surface during irradiation. A still further object of our invention is to provide an irradiator whereby separate bodies of liquids may be irradiated at the same time under the same conditions of irradiation from a source of ultra-violet energy. A still further object of our invention is to provide means for maintaining the liquid film supporting surfaces exactly vertical and also to provide means for maintaining the feeding slot on a curved surface exactly horizontal. Another object of our invention is to provide an apparatus in which all parts in contact with the liquid being irradiated are removable as a unit for cleaning.

These and other objects of our invention will in part be evident and will in part be set forth in the following specification, having reference to the accompanying drawings, in which:

Fig. 1 is a top view of an irradiator illustrating one embodiment of our invention.

Fig. 2 is a cross section of the film supporting shell taken on line 2--2 of Fig. 1.

Fig. 3 is a diagrammatic view showing the method of laying out the shape of said shell.

Fig. 4 is a vertical section taken on the line 4--4 of Fig. 1.

Figs. 5, 6 and 7 are detailed cross sections taken on the lines 5--5, 6--6, and 7--7 of Fig. 4 showing means for adjusting the position of the shell supporting the liquid film during irradiation.

It is now well known that irradiation of such liquid food stuffs as milk with various types of energy is desirable for the purpose of anti-rachitic activation, sterilization, etc. The irradiation of milk with ultra-violet energy to

produce anti-rachitic activation is becoming of increasing commercial importance. Heretofore, the apparatus has been of relatively large size or of very small laboratory size. We have devised an apparatus which is particularly adaptable for use in small commercial installations or in large scale laboratory investigations, but it may also be used in larger installations.

It is well known that the laboratory investigations of the degree of activation of various liquids, such as whole milk, skim milk, whey, or concentrated milk, are tedious and difficult. One of the reasons why such evaluations of anti-rachitic potency are difficult is that the testing of such products must be carried out by biological assays. In comparing the potency of various fluids it is essential that the fluids be irradiated under exactly the same conditions. This is not easy for various reasons. One of these is the fact that some sources of ultra-violet energy do not emit such energy at an absolutely constant rate. Hence, it is desirable that the samples to be compared be irradiated simultaneously from the same source of energy. We have devised an apparatus which permits of such irradiation.

In any irradiation of food products, and especially of dairy products, it is necessary that the devices used in treating them be cleaned frequently. It is well known that such products are subject to spoilage due to scouring, etc. This is due to the presence of bacteria. For this reason, among others, the apparatus must be thoroughly cleaned frequently. We have devised an apparatus in which the parts contacting with the irradiated liquid can be readily removed for frequent cleanings. Moreover all parts in contact with milk are removed as a unit and may be taken to a trough or the like for cleaning. This is an added convenience and reduces the danger of water coming in contact with the mechanism for producing ultra-violet energy.

In any demountable apparatus the parts are subject to slight variations in position upon re-assembly. In a device of the type which we have invented it is important that the parts be capable of adjustment upon assembly in order that they may be in correct position. In maintaining a thin film of liquid to be irradiated, such as a film of milk having a thickness of from .15 to .35 mm., if the milk distributing means is not level considerable variations in the thickness of the film may result. For this reason we have provided our device with means for adjusting the

position of both the milk trough and the irradiating screen after assembly.

In the embodiment of our invention illustrated in the accompanying drawings we have shown an arc lamp as the source of energy. While we have found an arc lamp using carbon electrodes with suitable flame materials in the core to be the best source of irradiation, our invention is not limited to such a source. In the drawings, there is shown an arc lamp A' having electrodes E and driven by suitable conventional apparatus contained in a housing H. The housing is secured to a frame work F which is formed in any suitable manner, as by substantially vertical angle member 10 and substantially horizontal angle members 11. The frame work may rest on any surface, such as the floor of the room in which the irradiation is being carried out. In order that it may be secured thereto, if desired, suitable members 12 are provided at the foot of the vertical member 10. The vertical members 10 are preferably arranged at the corners of a rectangle. The arc lamp with its housing H is mounted at one of the shorter sides of the rectangle. Opposite to the arc lamp housing there is provided a plate 14, since we prefer not to utilize this side of the device for irradiation purposes. However, it is within the scope of our invention to arrange the vertical members 10 at the corners of a square, pentagon, hexagon, etc. in which case three, four, five or more irradiating shells or screens would be provided instead of the two shown in Fig. 1.

On the two longer sides of the rectangle are arranged irradiating shells or screens. A cross section through one of the shells is shown in Fig. 2. The shell consists of a vertical film-supporting surface 16, an upper trough 17 and a lower receiving trough 18. The film supporting surface is curved as is shown in Fig. 3 and as will be described more in detail hereinafter. The upper and lower troughs 17 and 18 conform to the curvature of the milk supporting surface. The lower trough 18 is provided with an outlet 19.

The upper trough 17 is divided into two portions 22, 24 by a vertical partition or baffle 21 which is substantially parallel with the film-supporting surface 16. The outer portion 22 is provided with an inlet 23. The inner portion 24 is provided with a slit 25' extending through the film supporting surface 16. The purpose of this slit is to supply milk evenly to the film supporting surface 16. It has been found that the supplying of milk to a surface at a constant head and through a slit is an efficient means for securing a film of a given uniform thickness. The baffle 21 to prevent irregularities, such as swirls or eddies, in the flow in the trough of the fluid being irradiated from interfering with the even flow of the fluid through the slit. To effect this result it is not absolutely necessary that the baffle extend entirely to the bottom of the trough.

In the operation of the device the liquid to be irradiated, as for example milk, enters the outer portion 22 of the trough 17 through the inlet 23. The milk is evenly distributed in the outer portion of the trough and flows over the baffle 21 into the inner portion 24. It then flows outwardly through the slit 25' and down the film supporting surface 16 and is collected in the trough 18 from whence it is removed through the outlet 19. In ordinary operations under commercial conditions the two inlets of the separate troughs would be connected and the outlets of the lower troughs of the separate shells would be connected. However in case it is desired to con-

duct comparison tests on different liquids, one liquid would be introduced into the trough of one shell and the other liquid would be introduced into the trough of the other shell. In this case the irradiated liquids would of course be kept separate. By this means it is possible to irradiate different liquids under absolutely the same conditions for the purposes of comparison.

As shown above, the provision of two or more shells is of considerable advantage in case the irradiator is used in the laboratory. The same construction gives manifold advantages in commercial installations. The shells constituting the irradiating surface and the troughs can be removed for cleaning or other purposes. This is of especial importance in case the apparatus is used for irradiating milk. It is well known that extreme cleanliness is required in all dairy operations, since undesirable flavor and color changes would soon occur if bacteria were given an opportunity to develop. The simple provisions for the disassembly of the device is of marked importance in commercial as well as laboratory operations. Moreover, the demand for irradiated milk is subject to fluctuation. Milk is a perishable commodity and the irradiated milk cannot be stored for long periods of time. Accordingly it is desirable to have a device which will permit of some alteration in capacity and this without change in the operating characteristics. By using only one irradiating shell the capacity of the device may be cut in half and the operating conditions will be absolutely unchanged. Of course in case of an irradiator having more than two screens the variation in capacity would be even greater. In the past it has been possible to operate known irradiators at varying capacity only by disturbing predetermined film characteristics.

Furthermore, from a manufacturing standpoint the construction offers advantages. In case a customer desires an irradiator of a smaller capacity than that of the standard unit it is possible to ship him an irradiator having only one shell and with a blank sheet to occupy the position normally occupied by the other shell. The construction would be the same throughout and in case the customer eventually desired increased capacity it would only be necessary to provide him with the second shell which could readily be placed in position upon the removal of the blank sheet.

If still smaller units are desired for comparing the treatment of different liquids, each shell may be divided into two or more sections by providing baffles to separate the troughs 17 and 18 into sections and baffles on the treating surface to prevent the liquids from commingling. With this arrangement and a separate means for supplying and withdrawing liquids from the several sections, different liquids may be irradiated at the same time on each section of the shell.

It is, of course, desirable that the milk or other liquid being irradiated flow in a sheet of uniform thickness over the entire supporting surface. To do this it is necessary that the slit 25' be level throughout its length. Since the slit does not lie in a straight line but in a curve it is necessary to level the plane containing this curve. Under special conditions this might be done by rotating the plane in which the slit lies about a single axis but in general it is necessary to rotate the plane about separate axes. The most simple arrangement is, of course, to have these axes at right angles to each other. We have provided means for such adjustments and these means are

shown in detail in Figs. 4, 5, 6 and 7. The vertical angle members 10 are provided with studs 25 and 26, arranged preferably at equal heights as a matter of convenience. These studs consist of a threaded portion 27 and an outer portion 28 which is provided with a neck 29. One of these studs, as for example the stud 25, has its threaded portion extending through a hole 31 in one of the vertical members 10 as is clearly shown in Fig. 5. The stud 26 has its threaded portion extending through a slot 32 in the opposite vertical angle member as is shown in Fig. 6. The irradiator shell is provided with vertical members 34 at the ends thereof. These vertical members 34 are provided with slots which are in the shape of an inverted key hole. In assembling the irradiator shell on the supporting frame work the head of the studs is placed at the lower part of the key hole shaped slots. The irradiator shell is then allowed to drop slightly so that the neck of the stud engages the upper narrower portion of these slots. The head of the stud is of such size that it will pass through the lower enlarged portion of the slot but will not pass through the upper narrower portion of the slot. The irradiator shell is thus held firmly to the framework of the device. In case the two ends of the milk feeding slit are not level, the nut on the threaded portion of the stud 26 is loosened and adjusted up or down to the extent necessary to bring the two ends of the milk feeding slit into the same horizontal plane.

In case portions of the slit between the ends are not in the same horizontal plane with the ends it is necessary to make further adjustments. For this purpose adjusting members 41 are provided at each side as shown in Fig. 7. This adjusting member 41 consists of a bolt 42 threaded through the angle member 10. Suitable means 43 are provided whereby the bolt may be readily turned thereby moving the end of the bolt 42 with respect to the angle member 10. The ends of the bolts 42 engage the vertical members 34 near the bottoms of the ends of the irradiator shell and serve to tilt the irradiator shell about an axis passing through the upper surfaces of the stud members 25 and 26. By adjusting the bolts 42 in or out it is possible to bring any points intermediate the ends of the milk feeding slit into the same horizontal plane as its ends. Since the slit lies in a plane and since three points determine a plane this will insure that the entire slit is level. After this has been done the members 41 are locked in position by suitable lock nuts 44 which are conveniently wing nuts as shown.

Thus it will be seen that we have provided a simple and efficient means for keeping the milk feeding slit level. The milk feeding trough is fixed in position relatively to the milk feeding slit and the top of the partition or baffle 21 is then also level. Thus we have insured that there will be an even head of fluid throughout the circumference of the irradiator shell. This results in an even flow of milk throughout the circumference of the slit 25'. It is of course to be understood that each irradiator shell is separately adjusted.

Maximum efficiencies of irradiation are secured when the same intensity of energy is applied to each unit of surface of the film being irradiated. This is because it has been determined that certain intensities or periods of irradiation are most efficient and an endeavor is made to irradiate each portion of the film as this intensity and for this period. Irradiating a portion of the liquid for a

greater period and a portion for a shorter period thus giving the same average period is not as satisfactory. For one thing the rate of activation decreases rapidly after the period of maximum efficiency is passed. Hence, the over-irradiated liquid does not have an increased activation sufficient to compensate the under-irradiated liquid. Moreover, excess irradiation may cause undesirable changes, such as an undesirable odor or taste, or may even result in decreased activation. Similarly applying the radiant energy with uneven intensity upon the film surface results in decreased efficiencies. Thus in order to obtain maximum efficiency it is desirable to irradiate the entire surface of the film uniformly. Where circumstances permit, this can be done by having the milk flow over the interior surface of a circular cylinder with the source of energy at the center. However, it is often inconvenient or impossible to use such a surface because of the size of the arc lamp. In such cases it is preferred to shape the surface as hereinafter described to give uniform intensity of impingement of the rays throughout a larger arc of the surface.

It is known that the intensity of irradiation upon a surface normal to the direction of radiation varies inversely as the square of the distance from the source. It is also known that when the surface is inclined the intensity of the irradiation varies as the cosine of the angle of incidence. By taking advantage of these two factors it is possible to uniformly irradiate surfaces at varying distances from the source of energy in the same horizontal plane. Such an effect is secured in the device disclosed in our application. In Fig. 3 we show details of the development of a surface for an irradiator screen designed to secure an even intensity along a given horizontal cross section. Fig. 3 represents diagrammatically a cross section through the center of the arc lamp and one of the irradiator shells. The point O corresponds to the center of the energy source, i. e. the point of maximum intensity of the arc. A plurality of equal angles are laid off by lines passing through this point. These angles should be as small as convenient, but we have found that angles of 5 degrees give a contour of the section of the irradiator shell which is satisfactory. A distance L is laid off between two of the lines having an angle A between them. Ordinarily this would be laid off from the line which is to be the center line of the surface. An arc is drawn with radius L which will intersect the next adjoining line. Ordinarily this arc will intersect this line in two points, in which case the point nearest O is employed. The distance L should be slightly greater than the chord between two adjacent 5 degree radii. From this point, where L intersects the adjacent line, an equal distance L' is laid off intersecting the next line. This is continued around until a contour has been developed sufficiently large for the purpose desired. We have found that by using the angle as 5 degrees that good results are obtained when eight such 5 degree angles are laid off on either side of the center line. The points thus determined are connected by a smooth curve and this determines the contour of the cross section of the irradiator shell.

It will be evident that in this manner the average intensity of irradiation upon each area thus determined will be equal. Each width L of the vertical section is the same. The amount of light radiated in a pencil of rays having the same central angle A is the same. Hence equal amounts

of energy are impinged upon equal areas. Dividing the equal energies by the equal areas, it is obvious that equal intensity results. While it may be true that the energy intensity on every portion of this area is not absolutely constant yet we have found that by using the angle A equal to 5 degrees the departure of the intensity from the average is not sufficiently great to cause unfavorable irradiation conditions. In case such conditions were produced, we would of course make the angle A smaller than 5 degrees. As a matter of fact the use of a smooth curve instead of a plurality of straight lines connecting the points as determined as above set forth tends to make the conditions approach more nearly the theoretical shape in which absolutely even irradiation conditions are present.

Thus it will be observed that we have secured an irradiation device in which we have compensated for the fact that, under certain conditions, it is impossible to place the source of illumination at the center of a circular cylinder, and at the same time secured even irradiation over the surface of the film of liquid being irradiated. We have also provided an irradiating device which has means for insuring an even flow of liquid over the irradiating screens or surfaces and which may be easily disassembled for thorough cleaning and accurately reassembled to insure uniform flow. We have also provided a device which is very accurate in comparing the effects of uniform radiation upon samples of different materials. While we have disclosed one type of apparatus suitable for securing these and other novel features we do not wish our invention to be limited to this exact embodiment, as various modifications therein will readily occur to those skilled in the art.

We claim:

40 1. In a device for irradiating liquids, the combination of means having a film supporting surface, said means being provided with a slit near the top thereof; a receptacle on said means on the side opposite to said surface and extending above and below said slit and extending at least the length of said slit, said receptacle being provided with a baffle therein extending above and below said slit; and means for supplying liquid to said receptacle on the side of the baffle opposite said slit.

55 2. A shell for a liquid irradiating device comprising means forming a vertical surface provided with a horizontal slit near the top of said surface, a trough on the side of said means opposite said surface, said trough having its bottom below and its top above said slit and extending throughout the length of said slit, a baffle in said trough extending from the bottom of the trough above the top of said slit but terminating below the top of said trough, said trough being provided with an inlet on the side of the baffle opposite said slit.

60 3. A liquid irradiating device comprising a source of radiant energy, a substantially vertical curved irradiating surface, a slit in said irradiating surface, adapted to be positioned in a substantially horizontal plane, for supplying liquid thereto, and means for adjusting said irradiating surface to position said slit in a horizontal plane.

70 4. A device as defined in claim 3, including a pair of spaced pivotal members adapted to support said irradiating surface and means for adjusting said irradiating surface at right angles about said pivots.

75 5. A liquid irradiating apparatus as claimed in

claim 3 including a plurality of such adjustable surfaces positioned about the source of radiant energy.

6. A fluid irradiating apparatus comprising a source of radiant energy; at least one film-forming unit providing a surface on which a film of flowing liquid may be irradiated by said source of radiant energy, said surface having a slit therein adapted to be positioned in a substantially horizontal plane for supplying liquid to be irradiated on the surface in a thin flow of substantially uniform thickness; and means for supporting said film-forming unit, said supporting means comprising at least one pivot and at least one positioning member for adjusting the unit about an axis of said pivot.

7. A liquid irradiating apparatus comprising a source of energy, a supporting frame, and at least one film-forming unit supported by said frame; said film-forming unit comprising means forming a surface curved about a substantially vertical axis and adapted to receive energy from said source; means for distributing liquid over said surface, said means including a slit adapted to be positioned substantially horizontally; and means for receiving irradiated liquid from said surface; said unit being bodily removable from said frame for cleaning purposes; and means for adjustably holding said unit on said frame, said holding means including means for adjusting the unit about axes at substantially right angles to each other to level said slit over all portions thereof.

8. A liquid irradiating apparatus comprising, in combination, a source of radiant energy; an adjustable member having a surface at an angle to the horizontal for supporting a relatively wide film of liquid to be irradiated by such energy while said liquid flows downwardly over said surface, said member having an edge over which liquid is supplied to said surface, said edge extending transversely of said surface and being substantially as wide as the liquid film to be irradiated; and means for adjusting said member to position said edge accurately horizontally and thereby insure a substantially uniform supply of liquid to said surface over said edge, and thus maintain the thickness of said film substantially uniform across the entire width thereof.

9. A liquid irradiating apparatus as claimed in claim 7, in which said surface is curved about an axis extending in the direction of flow of said film, and in which such adjusting means is operable to adjust said member about axes in planes substantially perpendicular to each other.

10. An irradiating apparatus including a source of radiant energy and a surface not lying wholly in a single plane, which surface is adapted to receive liquid to be irradiated while flowing thereover, said surface being provided with an edge, adapted to be positioned substantially horizontally, over which a flow of such liquid is supplied to such surface, and means for adjusting said surface about axes substantially at right angles to each other to control the position of said edge relative to the horizontal.

11. An irradiating apparatus comprising a source of radiant energy and a surface not lying wholly in a single plane, which surface is adapted to receive liquid to be irradiated while flowing thereover; said surface being provided with an edge, adapted to be positioned substantially horizontally, over which a flow of such liquid is supplied to such surface, and means for adjusting said surface to control the position of said edge relative to the horizontal; said adjusting means

comprising a pivotal support and means for adjusting said surface about said pivotal support in directions substantially at right angles to each other.

5 12. In an irradiating apparatus, the combination of a substantially vertical, curved surface adapted to receive liquid to be irradiated during flow thereover, said surface being provided near the top thereof with a curved slit for supplying 10 a flow of liquid thereto, said slit being substantially normal to the direction of said flow; with means for adjusting the position of said surface about axes at substantially right angles to each other to level said slit over all portions thereof.

15 13. An irradiating apparatus comprising a source of radiant energy; a surface adapted to receive liquid to be irradiated while flowing thereover, said surface being curved about an axis parallel to the direction of flow of such liquid and provided with a curved edge, adapted to 20 be positioned in a substantially horizontal plane,

over which such liquid is supplied to such surface; and means for supporting and adjusting said surface to control the position of said edge relative to the horizontal, said means comprising a fixed pivot, an adjustable pivot, and a positioning member for adjusting said surface about said pivots. 5

14. An apparatus as defined in claim 1 including means for adjusting said first-mentioned means to control the position of said slit relative 10 to the horizontal.

15. An apparatus for irradiating liquid as defined in claim 7 in which the surface is curved and the adjusting means comprises an element serving as a pivot, and a plurality of positioning 15 means spaced from said element and from one another for adjusting said member about separate axes in planes at angles to each other.
